MAGNETO SHIELDING

Joseph J. Mascuch, Maplewood, N. J.

Original application July 11, 1931, Serial No. 550,076. Divided and this application July 3, 1937, Serial No. 151,956

6 Claims. (Cl. 123—148)

This invention relates to radio shielding and particularly to means for shielding magnetos.

The present application is a division of application Serial 550,076, filed July 11, 1931, and a continuation in part of application Serial 394,618, filed September 23, 1929. Where radio receiving equipment is used in proximity to internal combustion engines it is necessary to shield the ignition circuit to prevent interference with the radio reception. The shielding is accomplished by enclosing all parts of the ignition system in grounded metal casings which absorb and ground any electrical emanations which would adversely affect the radio equipment.

In the case of magnetos or similar units for the distribution of electrical energy, the frame or casing of the magneto is usually of metal and acts as a partial shield. It is customary, however, to leave the distributor blocks of the magneto exposed so that the ignition wires may be led from the distributor blocks to the spark plugs. Therefore, one object of the present invention is to provide means to completely shield a magneto by enclosing in metal covers the normally exposed distributor blocks and the ignition wires leading therefrom.

Magnetos are placed in different positions on different engines, and it is desirable that the ignition wires be led from the magneto to the spark plugs as directly as possible. Accordingly, a further object of the invention is to provide a shielding means which will permit the ignition wires to be led from the magneto in any desired direction. A specific object of the invention is to provide a rotatable elbow formation so that the ignition wires may be led to the spark plugs without the necessity of making any sharp bends in the wires.

The invention consists of the construction, combination and arrangement of parts, as herein illustrated, described and claimed.

In the accompanying drawing, forming part hereof, is illustrated one form of embodiment of the invention, in which drawing similar reference characters designate corresponding parts, and in which:

Figure 1 is a front elevation, partly broken away;

Figure 2 is a vertical section, partly in elevation, taken approximately on line 2—2 of Figure 1, looking in the direction indicated by the arrows;

Figure 3 is a side elevation on a reduced scale, showing the application of the invention to a

conventional magneto, the magneto being shown in outline; and,

Figure 4 is a front elevation, on a reduced scale, partly broken away, showing the invention with the magneto omitted.

Referring to the drawing, 5 designates a conventional magneto such as a "scintilla." Ignition wires 6 covered with usual insulation 7 lead from the distributor blocks (not shown) to the spark plugs of the engine. Normally, the distributor blocks and the ignition wires 6 are not shielded. The wires 6 emerge from the magneto 5 in a group and may be led to the spark plugs through a shielding system such as shown in application Serial 550,076. While the wires 6 are maintained together, as a group, they are preferably shielded by being enclosed in a flexible metallic sheath 8. The sheath 8 may be formed of braided metal having one or more layers and at its extremity is provided with a U-shaped ferrule 9. A ring 10 is secured to the outer portion of the ferrule 9 and abuts a coupling nut 11 which engages a threaded outlet 13 of a metal elbow 14. A gasket 12 is disposed in the outlet 13 adjacent the ferrule 9 to provide a liquidproof joint.

The lower portion of the elbow 14 is formed with a shoulder 15 from which depends an annular flange 16. The lower end of the elbow 14 terminates in a skirt 17 having therein an annular groove 18.

A pair of complementary cover plates 19 are provided to cover the distributor blocks. The plates 19 may be of any desired contour depending upon the structure of the magneto to which they are applied. The upper end of each plate 19 is formed with a substantially semicircular wall so that when the plates 19 are placed together there will be a single, substantially circular opening formed to register with the lower portion of the elbow 14 to permit the passage of the ignition wires 6. Each of the plates 19 is formed with bosses 20 and an annular flange 21. The plates 19 are held together by means of bolts 22 disposed through the bosses 20.

When the parts are assembled the skirt 17 of the elbow 14 is entered in the opening formed by the curved upper portion of the plates 19. The flange 21 interlocks with the flange 16 of the elbow 14 so that the elbow 14 is free to rotate with relation to the plates 19. Carried by one of the plates 19 is a setscrew 23 adapted to enter the annular groove 18 in the skirt 17. The screw 23 is adapted to hold the elbow 14 in

any desired angular relation with the plates 19 and prevent the unintentional removal of the elbow 14. Each of the plates 19 is provided on its inside surface with a leaf spring 24 which may be held in position by rivets 25. When the plates 19 are placed in position on the magneto and held together by the bolts 22, the springs 24 will maintain the plates 19 under tension so as to prevent vibration.

All of the wires 8 may be passed through the elbow 14 and thence through the sheath 8. In some installations it is desirable to provide auxiliary outlets so that wires may be led from the elbow 14 to a switch, booster magneto, etc. Accordingly, the elbow 14 may be formed with one or more outlets 26 through which wires 27 are led. The wires 27 are shielded by means of a flexible conduit 28, having a ferrule 29. A liquidproof joint between the conduit 28 and the outlet 26 is formed by means of a conical gasket 30, and a coupling nut 31 holds the parts together. The structure of the conduit 28 may be as shown in Patent No. 2,080,827, dated May 18, 1937, and the gasket 30 may be as shown in application Serial 731,833, filed June 22, 1934.

It will be understood that the casing of the magneto 5 is grounded. The plates 19, elbow 14 and sheath 8 are in electrical contact and grounded through the casing of the magneto 5. A complete radio shield is therefore afforded for the normally exposed portions of the magneto and the ignition wires leading therefrom. At the same time, it will be apparent that the elbow 14 may be rotated so that the wires 8 may lead from the magneto 5 in any desired direction.

Having thus fully described the invention, what is claimed as new and desired to be secured by Letters Patent is:

1. In a radio shielding means for the ignition system of an internal combustion engine, said ignition system including magneto, a pair of fixed complementary plates to cover the normally exposed distributor blocks of a magneto, the upper end of each plate being formed with a substantially semi-circular wall to provide a substantially circular opening for the passage of wires from the magneto when the plates are placed on a magneto and a shielding elbow rotatably mounted over the circular opening.

2. In a radio shielding means for the ignition system of an internal combustion engine, said ignition system including magneto, a pair of fixed complementary plates to cover the normally exposed distributor blocks of a magneto, the upper end of each plate being formed with a substantially semi-circular wall to provide a substantially circular opening for the passage of wires from the magneto when the plates are placed on a magneto, a shielding elbow rotatably

mounted over the circular opening and an outlet carried by the elbow.

3. In a radio shielding means for the ignition system of an internal combustion engine, said ignition system including magneto, a pair of fixed complementary plates to cover the normally exposed distributor blocks of a magneto, the upper end of each plate being formed with a substantially semi-circular wall to provide a substantially circular opening for the passage of wires from the magneto when the plates are placed on a magneto, a shielding elbow mounted over the circular opening and means to permit rotation of the elbow without removal thereof from the magneto, comprising a circular flange on the plates adapted to enter an annular recess on the elbow to support the elbow and a retaining means carried by one plate and extending into a groove in the elbow.

4. In a radio shielding means for the ignition system of an internal combustion engine, said ignition system including magneto, a rotatable elbow disposed on the top of a magneto to permit the passage of a plurality of wires from the magneto and outlets on the elbow to permit the passage of one or more wires to interconnect the several operating units of the ignition system.

5. A radio interference shield for the ignition system of an internal combustion engine, said system including grounded magneto having distributor blocks and spark plugs in circuit therewith, a two-part conductive casing straddling the distributor blocks, means in said casing to prevent vibration, a hollow elbow rotatable on said casing, said elbow being adjustably confinable and having a main outlet for conductors extending between the magneto and spark plugs, and a plurality of minor outlets disposed in different radial positions on said elbow for conductors leading to other members of the ignition system.

6. A radio interference shield for the ignition system of an internal combustion engine, said system including grounded magneto having distributor blocks and spark plugs in circuit therewith, a two-part conductive casing spacedly disposed over the upper part of the distributor blocks, resilient means in said casing to contact opposed sides of the magneto whereby to prevent vibration, an elbow rotatably confined on the upper part of said casing, means to clamp said elbow in an adjusted position, said elbow having a main outlet for the passage of conductors from the magneto to said spark plugs, a plurality of minor outlets arranged in different positions on said elbow for conductors leading to other parts of the ignition system, and metallic packings at each outlet setting the same.

JOSEPH J. MASCUCH.
